UNITED STATES PATENT OFFICE.

ROBERT ARTHUR THOMPSON, OF NEW ORLEANS, LOUISIANA.

ROAD-PACKING MACHINE.

Application filed July 17, 1925. Serial No. 44,336.

To all whom it may concern:

Be it known that I, ROBERT ARTHUR THOMPSON, a citizen of the United States, residing at New Orleans, in the parish of Orleans and State of Louisiana, have invented certain new and useful Improvements in Road-Packing Machines; and I do hereby declare the following to be a full, clear, and exact description of the invention, such as will enable others skilled in the art to which it appertains to make and use the same.

This invention relates to road packing machines and has for its object to improve those which have been heretofore proposed.

With this and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:—

25 Fig. 1 is a plan view of the road packing element of a machine made in accordance with this invention;

Fig. 2 is a sectional view of the parts shown in Fig. 1;

30 Fig. 3 is a side elevational view of the parts shown in Fig. 1;

Fig. 4 is a plan view of the drag element of the machine detached from that portion of the machine shown in Fig. 3;

35 Fig. 5 is a plan view of a portion of the parts shown in Fig. 4 detached from the drag; and

Fig. 6 is a sectional view taken on the line 6—6 of Fig. 5, looking in the direction of the arrows.

1 indicates a hollow central axle made in the form of a tube provided with the cap closing members 2 and 3 screw threaded on the ends of the tubular member 1, as shown, and 4 indicates a rectangular frame on which said tubular member 1 is mounted. Said frame extends entirely around the road packing element of the machine, as best illustrated in Fig. 1, and is provided at its corners with the corner plates 5 secured to the frame 4 as by the rivets or other fastenings, and said frame 4 is further provided on the inside of its corners with the angle bracing members 7, as shown. Thus is produced an exceedingly stiff and strong frame

work for the road packing element. To one of the members 8 of the frame 4 is secured the drag bar 9, as illustrated, and outside of the said drag bar is a flat strap-like steel member 10 which extends along the end portions of the frame 4 and terminates at the rear of said frame, as indicated at 11 on each end thereof. This said strap member 10 is secured to the frame member by the rivets 12 best shown in Fig. 3, and sustains practically all the pull or drag that is exerted on the machine, while the member 9 serves to center the pulling element or clevis 13, as will be readily understood.

The frame members 4 can be made of any suitable cross sectional material but channel irons are preferred, as best shown in Figs. 1 and 2. These said channel irons 4 at the end portions of the frame are suitably mounted or supported upon a square bearing block 15 at each end of the tubular member 1, as will be clear from Figs. 2 and 3. The frame 4 is, at each end of the tubular member 1, firmly held or secured to the said square bearing blocks 15 by any suitable means, as for example, by the U-shaped rod-like members 16 which pass down through the channel members 4 at each end of the device and encircle the said bearing blocks 15, and on their free ends are secured as by the nuts 17 as best shown in Figs. 2 and 3. In order to hold the members 16 in place, it is convenient to provide the bearing blocks 15 with indentations on their under sides as indicated at 18 in Fig. 2. Further, in order to more securely hold the bearing blocks 15 in place they are provided with projections 19, see Fig. 2, that extend through perforations or orifices in the tubular member 1, as will be clear from the drawings. These projections 19 have the further function of preventing the tubular axle 1 from rotating. Mounted upon said tubular axle 1 are a plurality of disk-like members 21 each provided with a strengthening rib 22 on each side and with a hub-like member 23, as shown. Said hub-like members 23, as best illustrated in Figs. 1 and 2, are adapted to form broken or lap-joints with each other. That is to say, the hub-like member 23 of one disk member 21 is disposed relatively close to the tubular member 1, while the succeeding hub-like member 23 is disposed further away from the tubular member 1 and overlies the extending portions of the 110

adjacent hub-like members 23 on each side thereof, the effect being to provide a broken or overlapping joint 24 due to the nesting of the hubs 23 between the various disk-like members 21 as shown, thus providing a means of preventing dust, dirt, or other foreign matter from going down into said joint 24 with the consequent separating of the disks 21 and possible injury to the tubular axle 1. Inside each disk-like member 21 is a ring or annular shaped bushing 26 preferably made of bronze or other suitable material and which comes in contact with the outer surface of the tubular member 1.

15 The purpose of making the members 26 of bronze is to reduce the friction and to provide a better wearing surface. The said tubular axle member 1 on its bottom side, as best shown in Fig. 2, is provided with numerous perforations 28 preferably two perforations to each bronze bearing member 26 and at each end of the tubular axle member 1 is preferably provided an oil cup 29 for the purpose of automatically supplying oil 20 to the interior 30 of the tubular axle 1. This oil finds its way continuously through the perforations 28 to the bronze bearing members 26 and thus keeps the road making disks 21 well lubricated.

25 30 To the rear members 11 of the frame 4, as at 31, is secured a chain or other attachment 32, to which may be secured the drag member designated as a whole by the numeral 33. This drag member is provided 35 with links or other attachments 34 on each side which are adapted to be attached to the hook-like members 35 of the chain 32, (only one of which members 35 are shown), and thus is the drag member as a whole pulled 40 along the surface of the road after the road-making member designated as a whole by the numeral 37. The said drag member 33 is provided with a pair of scraping members 38 secured together as by the short bar 39 45 and the longer bar 40, as illustrated in Fig. 4, and said bars 39 and 40 are secured to each other by cross bars 41 and 42. The lower edges 43 and 44 of the members 38 are so disposed as to lie entirely upon the 50 surface of the road to be smoothed or scraped while they are inclined to each other at an angle, as illustrated in Fig. 4. These said scraping members 38 are of unequal lengths as shown and the edge 43 of one of said 55 members is preferably made to extend beyond the edge 44 of the other members, so that a smoother disposition of the road material is had than would be the case if the bars 38 were made of equal length. The 60 members 38 are conveniently made of any suitable material as illustrated and are provided with angle bars 45 and 46 of steel in order to stiffen the same as will be clear from Figs. 4, 5 and 6. These said angle bars 65 45 and 46 further provide a convenient

means for attaching the ends of the cross bars 39 and 40, as will be clear from Fig. 4, thus enabling one to produce expeditiously and at a minimum of cost an exceedingly rigid and strong drag frame adapted to perform the work that is required of it. Further, as will be clear from Fig. 6, the scraping members 38 are disposed at an angle of about 45° of the road to be scraped when the drag is in operation.

75 The operation of this road making machine will be clear from the foregoing, but may be briefly summarized as follows: Any suitable power, either horse power or traction power, may be attached to the member 13, while the drag member 33 is attached to the rear of the road making member 37, as by the hooks 35, and the entire device is dragged over the surface of a newly made road. The individual disks 21 will produce 80 furrows in the surface of this road, thus impacting or solidifying the material to an extent, while the drag member 33 will follow after the disks 21 and serve by its scraping edges 43 and 44 to pull over the material lying 85 between the furrows produced by the disks 21 and to thus fill up said furrows to a greater or less extent. After this action is had, the surface of the road will be more or less impacted and relatively smooth. 90 The machine is then carried over the road again making a new set of furrows and having said furrows again filled by the scraper members 38, and the process is repeated until the surface of the road is impacted and rendered smooth or solid. Of course, the disks 21 being more or less thin in cross section, they will sink to greater or less depths into the road material, especially at 95 first and they will clog up with dirt and road making material in between their surfaces, and especially in between their ribs 22. To render the device self-cleaning, there is attached to the under side of the frame 100 4, as best illustrated in Figs. 1 and 3, a scraping plate 50 provided with the slightly bowed and forwardly bent cleaning fingers 51 which fit in between the ribs 22 and the disks 21, as shown. This plate 50 and fingers 21 are preferably made of steel and 105 serve to automatically clean the said disks 21, as will be readily understood.

110 It is obvious that those skilled in the art may vary the details of construction as well as the arrangement of parts without departing from the spirit of the invention, and therefore it is not desired to be limited to the foregoing disclosure except as may be required by the claims.

115 120 125 What is claimed is:—

1. In a road packing machine, the combination of a hollow axle; a plurality of road packing disks rotatably mounted with relation to said axle and provided with laterally extending overlapping hubs to 130

form a broken, dust excluding joint; and means for automatically lubricating said disks while the device is in operation.

2. In a road packing machine, the combination of a hollow axle; a plurality of road packing disks rotatably mounted with relation to said axle and provided with laterally extending overlapping hubs to form a broken, dust excluding joint; a frame surrounding said disks and mounted on said axle; and means for automatically lubricating said disks while the device is in operation.

3. In a road packing machine, the combination of a hollow axle; a plurality of road packing disks provided with nested hubs rotatably mounted with relation to said axle; a frame surrounding said disks and mounted on said axle; disk cleaning members secured to said frame and disposed between said disks; and means for automatically lubricating said disks while the device is in operation.

4. In a road packing machine, the combination of a hollow axle; a plurality of road packing disks provided with nested

hubs having ring like wearing bushings rotatably mounted with relation to said axle; a frame surrounding said disks and mounted on said axle; bearing blocks preventing said axle from rotating and supporting said frame; and means for automatically lubricating said disks while the device is in operation.

5. In a road packing device, the combination of a hollow perforated axle; bearing blocks fitted to said axle and preventing the latter from rotating; closures for the ends of said hollow axle; means for supplying a lubricant to the interior of said axle; a plurality of road making disks provided with nested hubs mounted for rotation on said axle and adapted to receive said lubricant; a frame mounted on said bearing blocks; a plurality of cleaning members carried by said frame and disposed between said disks; and means for rolling said disks over the surface of a road.

In testimony whereof I affix my signature.

ROBERT ARTHUR THOMPSON.
